PACKAGED ELECTRODES FOR THE CA-
THODIC PROTECTION OF METALLIC
UNDERGROUND STRUCTURESRobert B. Mears, Oakmont, Pa., assignor to Alu-
minum Company of America, Pittsburgh, Pa., a
corporation of Pennsylvania

Application October 25, 1946, Serial No. 705,508

3 Claims. (Cl. 204—197)

1

This invention relates to a novel electrode or anode package designed for use as a part of an installation designed to protect metallic underground structures, such as pipe lines, oil well casings or parts, structural footings and the like, against corrosion and corrosive agents or agencies. In such installations a metal electrode, made of metal anodic to the metal of the structure to be protected, is buried in the earth at a distance from the metallic underground structure and connected thereto by a conducting wire or bus thereby forming a galvanic cell, the earth serving to complete the circuit. When such installations are properly made, a steady current flows continuously in the cell so formed and offers, as is well known, considerable protection against corrosion to the buried metallic structure.

The present invention relates to improvements in such installations being primarily directed to the provision of an improved electrode assembly or package of very considerable advantages. The objects, purposes and advantages of the invention are best described with reference to the accompanying drawings, in which:

Fig. 1 is a diagrammatic representation, shown in cross sectional elevation, of a portion of a typical installation made in accordance with prior practice, to cathodically protect a metallic underground structure;

Fig. 2 is a view in cross sectional elevation, through an electrode package embodying this invention in preferred form;

Fig. 3 is a view of a cross section through the package shown in Fig. 2, taken at the section line 3—3;

Fig. 4 illustrates, in cross sectional elevation, another electrode package embodying the principles of this invention.

Discussion of the conventional installation illustrated in Fig. 1 will serve to illustrate the reasons for and the advantages of the present invention. The metallic underground structure to be protected is illustrated by a pipe line 10 buried in the earth 11. An electrode 13 is buried a distance from the line 10 and connected thereto by the wire 12. Usually a number of electrodes are employed when a buried linear structure, such as a pipe line, is to be protected, the electrodes being spaced along the run of the line at

suitable intervals and connected to the line as illustrated in the figure. Only one electrode is shown in the illustration. In some installations a series of single electrodes is connected at intervals along the pipe line. In other installations groups of electrodes may be disposed at intervals along the line, each group being connected to the line with a single lead. The electrode 13 is installed in a hole dug in the earth, the outline of the hole being indicated in Fig. 1 by the broken line 14. The electrode is positioned in the hole and then maintained in this desired position by tamping or pressing the mixture 15 around it. Thereafter, in usual practice, an earth cap 16 is placed on top of the mixture 15 to fill the hole to the earth level 17. The mixture 15 is prepared at the time of installation and comprises a carrier or base, often formed of earth, with which are mixed chemicals of predetermined nature and quantity. These chemicals have various functions but are usually considered necessary to promote efficient operation of the electrode and of the cell of which the electrode is a part. The chemicals, the exact nature and quantity of which form no part of this invention, often differ according to the composition of the metallic electrode 13, the nature of the current desired in the cell and the judgment of the person making the installation. In any event, the chemical substances are predetermined as an active element of the installation. As above stated, the metal of the electrode is anodic to the metal of the structure to be protected, and since such structures are usually made of iron or steel, it has been common practice to use zinc electrodes. Recent developments in the utilization of aluminum and magnesium metals as electrodes have opened the commercial utilization of these metals. Whatever the metal chosen as electrode, and the chemicals chosen as the active element of the mixture or "backfill" surrounding the installed electrode, the practice of installation has been as described, the mixture being made, at the time each electrode is installed, from materials brought to the field and then pressed or tamped around the electrode. Besides requiring an undue amount of time and transportation of chemicals to the field, such backfilling operations have required constant supervision to make certain that the backfill mix-

tures are of proper concentration. This is true not only at the time the electrodes are installed but also when replacement of the electrode is necessary.

These distinct disadvantages of the present installation practices are overcome, the job of installation and replacement simplified and accuracy of the final result insured by the present invention.

In accordance with this invention a preformed electrode package is prepared which essentially consists of a metallic electrode of desired composition surrounded by a rigid permeable envelope containing the chemical components predetermined as the desired active elements in the final installation. Thus electrode and envelope comprise a single unit. In practice this packaged electrode may be transported as such to the place of installation, dropped, or planted, in a hole dug to receive it and the installation finished by connecting the electrode to the structure to be protected. Thereby the necessity for preparing a mixture in the field is avoided, accuracy of mixture is assured and the work of installation considerably lessened. Such electrode packages are, I have found, as efficient in operation as the field-assembled installations which they replace, and in some instances there have been indications that over extended periods of time the operation of the galvanic cell of which the installed package is a part is more efficient.

The preformed electrode package of this invention may take various shapes and forms. Examples are illustrated in Figs. 2 to 4, inclusive. The package is formed by casting or pressing or otherwise forming on the selected electrode a rigid mass which contains the active chemical elements. Such a form of package is shown in Figs. 2 and 3, a rigid cement envelope 19 having been cast upon the metallic electrode 18. In this case the package has also been provided with a connecting lead 20, the point of attachment of the lead to the electrode 18 having been covered with a protective cap 21, here made of asphalt, to prevent undue corrosion at this point. In the form shown in Fig. 2 the rigid envelope 19 entirely surrounds the electrode but such construction is not necessary and only a substantial portion of the electrode surface need be covered. Thus in the form shown in Fig. 4 the rigid permeable mass 23 only covers a portion of the electrode 22, the wire lead 24 and the protecting cap 25 being again conveniently provided. In these forms the rigid mass or envelope 19 or 23 may be formed of cement, plastic, ceramic, some forms of gelatin, or other moldable substance which, when molded into contact with the electrode, forms a rigid permeable envelope or coating.

The term "rigid" as used herein means that the mass surrounding the electrode should have sufficient stiffness to be self supporting. The envelope or coating must be of such a character as to allow any liquid and chemical to come in contact with the electrode and this property is herein designated as permeability. In most cases the surrounding mass will have channels or pores of a sufficient size to be readily detected and herein masses of this nature are regarded as being porous.

The chemicals required in the mass may in many cases, depending on the chemicals desired and the material of which the mass is formed, be mixed with the mass prior to placing it around the electrode or a neutral mass may be employed and after it is placed on the electrode

the required chemicals may be placed in its pores by immersion of the article in a solution of the chemical, followed by drying, or by familiar methods of pressure impregnation or in any other convenient manner.

Other substances than the required chemicals may be present but they should not, of course, destroy the effect of the chemicals. Also in particular cases it may be desirable to apply first 10 a coating to the electrode with a chemical which alters rate of reaction with the surrounding envelope before molding or casting the said envelope about the electrode.

In any event, the result is an electrode package 15 consisting essentially of a metallic electrode at least partially enveloped in a rigid permeable mass, the mass containing chemical predetermined to be an active element in the cathodic protection installation of which the unitary package will become a part. While exact compositions form no part of this invention, some examples thereof will serve to illustrate the invention in its preferred form. For instance, if 20 the package contains a zinc or magnesium electrode, the permeable envelope may be formed of a calcium sulphate cement or a Portland cement to which sulphates have been added, since sulphates are chemicals often chosen for the backfill mixture when such electrodes are used. If 25 the electrode be of aluminum and it is desired to use an alkaline backfill mixture of substantial halide content, such as the mixtures proposed by R. H. Brown in his copending application, Serial No. 693,593, filed August 23, 1946 (now Patent No. 2,565,544), the envelope element of the package may be formed of an alkaline cement in 30 which amounts of halides have been incorporated. Good results have been obtained with a package consisting of an aluminum electrode surrounded by a rigid permeable mass made of cement consisting of a mixture of equal parts of magnesite and sand moistened to a paste consistency, prior to molding, by a saturated solution of magnesium chloride.

Cements generally are preferred in the construction of the electrode package of this invention because of their inherent chemical composition, their protective qualities, their permeable nature and the ease and cheapness of the operation of casting the cement around the electrode to form a unitary preformed electrode package which may be readily handled and transported.

The words "aluminum," "magnesium" and "zinc" are used herein to designate the metallic nature of the electrode and are used in the sense of aluminous, magnesic or zincous metals and are, therefore, not intended to exclude, by implication or otherwise, alloys containing these metals in such quantities as to make such alloys useful in a cathodic protection system.

Having thus described my invention, I claim:

1. In a cathodic protection system an underground metallic structure, said structure being electrically connected to a separately installed underground electrode of a metal anodic to the metal of said structure, and said electrode being at least partially enveloped and fixedly contacted by a rigid cement mass containing chemical predetermined as an active element in said system, said mass being permeable to liquid.

2. In a cathodic protection system an underground metallic structure, said structure being electrically connected to a separately installed underground aluminous electrode, said electrode being at least partially enveloped and fixedly con-

tacted by a rigid cement mass containing chemical predetermined as an active element in said system, said mass being permeable to liquid.

3. In a cathodic protection system an underground metallic structure, said structure being electrically connected to a separately installed underground magnesic electrode, said electrode being at least partially enveloped and fixedly contacted by a rigid cement mass containing chemical predetermined as an active element in said system, said mass being permeable to liquid.

ROBERT B. MEARS.
